UNITED STATES PATENT OFFICE

NICOLAE IVANOVICI, OF BUCHAREST, RUMANIA

MACHINE FOR GRINDING AND POLISHING FLOORS

Application filed September 6, 1927, Serial No. 217,800, and in Rumania September 15, 1926.

The machines at present in use for the cleaning of floors are for the most part electrically actuated and are drawn over the floor. They are without exception suitable for the waxing and polishing of parquetry and also for the waxing and shining of mosaic, terrace and other floorings, but fail when it is a question of grinding off such floors, that is, preparing them by means of a preliminary operation for the waxing and polishing, without meanwhile grinding away too much material from the floor surface.

A further great disadvantage of such machines is that their specific working load, under which the aforementioned measures are carried out, cannot be adapted to the particular work to be done. The makers of such machines have hitherto consulted their own convenience by making the machines of a medium weight. Such an invariable weight, however, in the case of the grinding operation loads the surface to be ground insufficiently, but in the case of polishing it loads the surface that is to be polished too much, or in other words the machines have an incorrect loading for both operations. This dilemma also leads to other defects, which will be hereinafter more fully discussed, and which the present invention is intended to eliminate.

30 The invention is illustrated by way of example in the accompanying drawings, where-in

Fig. 1 is a side elevation of a grinding and polishing machine.

35 Fig. 2 is the same machine in plan.

Figures 3 and 4 show in plan and side elevation respectively an abrading disc having a flexible support with grinding stones secured to it.

40 Figures 5 and 6 show in plan and side elevation respectively a modified form of abrading disc having a pressure equalizing support in the form of a coiled tube.

Figures 7 and 8 show in cross section two 45 forms of grinding stones adapted to be secured to the flexible support by means of clamping rings.

Figure 9 is a detail view in elevation partly in section showing a grinding stone with a 50 clamping ring for fastening the same to the

flexible support and Figure 10 is a plan view of a detail thereof.

Figures 11 and 12 show in elevation and in cross section respectively another form of clamping ring for securing grinding stones to the flexible support. 55

Referring to the drawings, the body A of the machine is connected by pivoted arms E to a shaft C' on which are mounted wheels C and a handle D by means of which the machine can be drawn along the floor. Rotatably mounted on the body A is an abrading disc 4, the face of which is parallel to the surface of the floor, said disc having a vertical spindle 5 journalled in the body A. 60 A flexible support 1 is removably attached to the disc 4, said support consisting of a sheet of linen or other fabric, india rubber or leather cloth. This flexible support as shown in Figures 3 and 4 has at its four corners 2 fastening means 3, which in the construction illustrated consist of press buttons and engage corresponding sockets (not shown) in the disc, said sockets being in the underside of the disc in Figure 8. While in the constructional form illustrated, the fastening means consist of press buttons, it is to be understood that the invention is not limited to such fasteners, since the flexible support 70 can be attached to the disc 4 by other suitable fastening devices, such as hooks. Attached to the support 1 are a number of grinding stones 6 of emery, carborundum or other suitable abrasive material and which may be of any desired shape. In the constructional 75 form shown in Figures 3, 4 and 5, the stones 6 are circular and are cemented at one end to the flexible support 1 at certain distances apart so that the dust produced by the grinding operation is ejected from between them 80 by centrifugal force. Between the flexible support 1 and the disc 4, a resilient body B is interposed which acts as a pressure equalizing support which enables each grinding stone 6 to yield independently of the others 85 to irregularities in the surface of the floor, whereby each stone is pressed with an equal specific pressure against the floor even when the surface of the latter is uneven. Not only 90 are the stones capable of yielding lengthwise 95

100

but they are also capable of tilting upon the pressure equalizing support B. A suitable form of pressure equalizing support is shown in Figures 5 and 6 and consists of an india rubber tube 24 coiled into a spiral.

The gluing or cementing of the stones on to the cloth support has in general proved satisfactory, but under some circumstances, particularly in the case of uneven floors, and in damp neighbourhoods, it is better to secure the stones to the linen or the like by means of positive anchoring devices. Figures 7 and 8 show cross sections of grinding stones of a shape which enable fastening devices to be employed which are satisfactory and cheap to manufacture, the stones 10 being provided with a cylindrical upper portion 20 and a dovetail lower portion 21, which in Figure 7 is undercut, while in Figure 8 the dovetail base of the stone is larger than the upper working face.

Referring to Figures 9 and 10, the stone 10 is attached to the flexible support 1 by means of a conical clamping ring 10a having a number of lugs 18 which are passed through the flexible support 1 and through slots 23 in a circular plate 22a, placed under the support beneath the stone 10, the lugs 18 being bent inwardly over the plate 23 towards the centre thereof so as to lie flat against the plate. By this means the stone is secured simply, durably and cheaply. The ring can frequently be used again, after the stone has worn down, for the attachment of a fresh stone. The claw ring shown in Figures 11 and 12 serves the same purpose and is particularly suitable for the attachment of the stone shown in Figure 7. The claw ring consists of a round plate 22 with a plurality of claws 17 (in the present case six), which are bent upwards and are pressed inwardly until they hold the stone firmly all round, as shown in Figure 12. The stone can in this case be secured to the ring before it is secured to the flexible support 1. For securing it to the latter the ring 22 is provided with spikes 18' (outside) and 19 (inside) which are passed through the support 1 and bent through about 90° over a metal ring 23'. The claw ring 22 has the advantage that the stone can be removed after wear by opening the claws 17, and a fresh stone secured in the claws by bending them back again. The upper part of the actual ring can be secured movably in a hinge by a pin or the like. Besides being secured by the metal ring, the stone may also be glued or cemented to the fabric.

In cases where it is only a question of rubbing floors which have already been ground smooth, it is sufficient to fasten the flexible support with the stones to a cleaning brush B, which in such cases, owing to the elasticity of its bristles, offers sufficient equalization of the pressure. Such a case is shown in Figure 4,

but in all other cases it is advisable to select pressure-compensating supports.

The machine is built as light as possible, and by putting on stones of different weights, a different and correct loading of the grinding disc can be obtained, corresponding to each particular operation to be carried out. Furthermore the centre of gravity of the grinding machines is not always in the position that is most advantageous for the grinding, brushing, or polishing. Thus for example by the lateral thrust of the handle D by which the machine A is drawn over the floor, lateral forces are set up which tend to tilt the machine. Furthermore it is not always a matter of indifference at what height from the floor the centre of gravity of the machine is located. In the case of all the machines at present in use, however, the position of the centre of gravity cannot be altered. In the case of the apparatus according to the present invention, however, the position of the centre of gravity can be quite considerably altered by placing or suspending the loading weights lower down or higher up as required, or even placing them eccentrically in relation to the machine body. Thus for example with the machine according to Figs. 1 and 2, it is possible to alter the weights 11, 12, 13 and 14 individually, or several together, and to alter the specific loading, and the position of the centre of gravity may also be made eccentric or shifted downwards. The weight 16 presses the centre of gravity further downwards and displaces it eccentrically, while by means of the superposed weights 15 and 15' the centre of gravity is shifted upwards.

The putting on of additional weights in machines of a minimum weight has further the great advantage that the coarse, cheap loading weights can be made everywhere, whereby a good deal can be saved in freight charges and customs duties on such machines. The considerably smaller weight of the machine makes it more suitable as an auxiliary motor in kitchen use, agriculture and the like, and in houses of several stories it is possible to keep the cheap loading weights on each floor and only carry the lighter machine from one story to another.

By constructing the abrading member in the form of a plurality of separate grinding stones attached to a flexible support which rests against a pressure equalizing device, the abrading member is capable of accommodating itself to the slightest irregularities in the surface of the floor, the pressure equalizing device shown in Figures 5 and 6 constituting a fluid filled cushion upon which the grinding stones are freely tiltable in all directions as well as being capable of moving bodily upwards from the floor.

What I claim is—

1. In a floor dressing apparatus, a dress-

ing tool comprising a disc, a pressure equalizing device on the outer face of the disc, a flexible support passed over said pressure equalizing device and attached to the disc, and a plurality of grinding stones attached at one end to said flexible support so that each stone will be capable of yielding and tilting about the center of its place of attachment.

10 2. In a floor dressing apparatus, a dressing tool including a disc-like brush, a piece of flexible material passed over the faces of the brush and fastened to the back of the disc-like part thereof, a plurality of grinding stones, and means for separately connecting each of the grinding stones to the outer face of the flexible material in such manner that they are capable of yielding and tilting about the centers of their places of attachment.

20 In testimony whereof I have signed my name to this specification.

NICOLAE IVANOVICI.
